UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

REGISTER-CONTROLLING SYSTEM.

Application filed September 21, 1923. Serial No. 663,976.

This application is a continuation in part of the application of Lundell and Clark, Serial No. 301,891, filed June 5, 1919.

This invention relates to a telephone exchange system and more particularly to systems in which registrations must be set up and transferred.

It is an object of this invention to provide an improved register controlling system.

In machine switching systems, the speed with which pulses are transmitted is a large factor in the control of the machine switching apparatus for making service connections from one subscriber to another. The setting of a large number of registers at one time through an impulse generating device makes it possible to reduce materially the number of combinations of apparatus and switches necessary to provide paths for the large number of telephone calls transmitted through a telephone exchange of this type.

The utility of a rotary impulsor switch for setting a plurality of registers is shown in the patent application of A. E. Lundell and E. H. Clark Serial No. 654,106, filed July 27, 1923 and in the Patent No. 1,501,676 to A. E. Lundell and J. J. Wynne issued July 15, 1924.

A feature of this invention is in the use of an impulse generating device for simultaneously setting a plurality of registers.

A further feature of this invention is in the particular arrangement of the relays constituting the register.

These and other features of the invention will be apparent from the following description taken in connection with the accompanying drawings.

While the invention has been disclosed as particularly adapted for setting registers of a machine switching system, it will be apparent, however, from the following description that the invention has a wider utility and that by slight modification, it could be adapted for use with other types of apparatus in which speed of setting registers is a desired object.

Fig. 1 illustrates the apparatus and circuits for controlling the setting of register relays shown in Fig. 2. Fig. 2 illustrates

two sets of register relays and associated lamps. Fig. 3 illustrates the order in which the drawings should be arranged.

Description of apparatus.

The rotary impulsor switch 510 is preferably of cylindrical form but to make the disclosure more readily understood, the cylinder has been developed into a plane rectangular surface. The cylindrical form may be of a type similar to a rotary commutator with numerous segments. It may be constantly driven from any suitable source.

Switches 300 and 400 are of a well known step-by-step type operated from a self-interrupting magnet. These switches are shown diagrammatically. Their complete utility however, is described in detail in the patent application of Alben E. Lundell and Edgar H. Clark Serial No. 654,106, filed July 27, 1923.

General description.

The circuit paths over which register relays 607 to 610 operate are carried through the contacts of relay 231 to brushes 526 to 529 of the impulsor switch. Upon each revolution of the impulsor switch, ground is successively connected to brushes 526 to 529 through segments 537 to 540. It is apparent that if relay 231 is operated when one of brushes 526 to 529 is engaged with one of segments 537 to 540, a register relay is operated. Therefore, any of the register relays 607 to 610 may be operated during one revolution of the impulsor switch by connecting the circuit path over which relay 231 operates to a brush brought into engagement with segments in a horizontal plane with segments 537 to 540. Brush 513 is brought into engagement with segments 531, 532 and 533.

With the operating path for relay 231 connected to brush 513, relay 231 is operated, when segment 537 is engaged with brush 526, when segment 538 is engaged with brush 527 and when segment 540 is engaged with brush 529. Therefore, three of the register relays are operated to light a particular lamp. The circuit path to light each lamp is established by the actuated or non-actuated

ated position of certain ones of the register relays.

A second set of register relays 611 to 614 are shown and are operable under the control of relay 229. A large number of like sets of register relays may be controlled and positioned in the same space as required for setting a single set. The number of relays per set may be increased by increasing the 10 number of segments and brushes on the impulsor.

Detailed description.

Let it be assumed that switch 300 is actuated to associate brushes 341 and 344 with the contacts connected to conductors 340 and 343, respectively. Again let it be assumed that switch 400 is actuated to associate brushes 440 and 443 with the contacts connected with conductors 441 and 445, respectively. Upon the positioning of switches 300 and 400, let it be assumed that relay 602 is actuated to establish a circuit path for relays 226 and 227. The detailed operation 25 of switches 300 and 400 and relay 602, with their associated circuits, is described in detail in the patent application of Lundell-Clark, Serial No. 654,106, filed July 27, 1923.

A circuit is now established to operate 30 relays 226 and 227 which may be traced from grounded battery through the windings of these relays in multiple, contact and armature of relay 602, right continuity contacts of relay 226, resistance 290, brush 511 to ground through segment 512 of rotary impulsor switch 510. The operation of relay 226 establishes a locking circuit for itself and for relay 227 which may be traced from grounded battery through the windings of 35 these relays in multiple, contact of relay 602, right contact and armature of relay 226 to ground through key 291. The operation of relay 226 further establishes actuating circuits for relays 229 and 231.

As described in the aforementioned patent application of Lundell-Clark the apparatus of Fig. 2 and the apparatus of Fig. 1 with the exception of switches 300 and 400 and the rotary impulsor switch 510 is all 40 located in the operator's position of the switchboard. Conductors such as 340 and 343 connect the armatures of relays such as 226 in the various operator's positions with the various contacts of switch 300. The 45 brushes 341 and 344 are those rotated for association with conductors extending to a particular operator's position.

The circuit for actuating relay 229 may 50 be traced from grounded battery through its winding, conductor 253, left inner contact and armature of relay 226, conductor 343, brush 344 and its associated contact, brush 443, and its associated contact, conductor 445, brush 514 to ground successively through

commutator segments 535 and 536 of the 55 constantly rotating impulsor switch 510. The circuit established to actuate relay 231 may be traced from grounded battery through its winding, conductor 254, left outer contact and armature of relay 226, conductor 340, 60 brush 341 and its associated contact, brush 440 and its associated contact, conductor 441, brush 513 to ground successively through the segments 531, 532 and 533 of the 65 constantly rotating impulsor switch 510. 70

As brought out in the general description, upon each revolution of the impulsor switch, ground is successively connected from segments 537, 538, 539 and 540 to impulsor switch brushes 526, 527, 528, and 529. It 80 is now apparent that during the time the actuating circuit is established for relay 229 from ground through segment 535, also during the time that a circuit is established for relay 231 to ground through segment 531, 85 a circuit is established from ground through commutator segment 537, brush 526, conductor 232 over a divided path through the contacts and armatures of relays 229 and 231. The path through the contacts of relay 231 may be traced from conductor 232, left outer armature and contact of relay 231, conductor 245, left winding of relay 607, to grounded battery, operating relay 607. 90 The circuit path through the contacts of relay 229 may be traced from conductor 232, through the left outer armature and contact of relay 229, conductor 250 to grounded battery through the left winding of relay 611, operating relay 611. Relays 607 and 611 100 in operating establish locking circuits for themselves from grounded battery through their right windings, right inner contacts and armatures to ground through contacts of key 291. 105

Upon further rotation of impulsor switch 510, circuits are again established to operate relays 229 and 231 through impulsor switch segments 536 and 532 respectively. During the time that these circuits are established a 110 circuit is established from ground through commutator segment 538, brush 527, conductor 233 over a divided path through the contacts of relays 229 and 231. The circuit through the contacts of relay 231 may be 115 traced from conductor 233, left inner armature and contact of relay 231, conductor 244 to grounded battery through the left winding of relay 609. The circuit through the contacts of relay 229 may be traced from conductor 233, left inner armature and contact of relay 229 conductor 247 to grounded 120 battery through the left winding of relay 613. Relays 609 and 613 are actuated and establish locking circuits for themselves from grounded battery through their right windings, right inner contacts and armatures to ground through the contacts of key 291. 125

Upon further rotation of the impulsor switch 510 a further circuit is established to operate relay 231 from ground through commutator segment 533. In this horizontal 5 plane of the impulsor switch segments, a circuit is not established to operate relay 229. During the time that relay 231 is operated, a circuit is established from ground through impulsor switch segment 540, brush 529, conductor 235, right outer armature and contact of relay 231, conductor 242 to grounded battery through the left winding of relay 608. Relay 608 is actuated and establishes a locking circuit for itself from grounded battery 10 through its right winding, right inner contact and armature to ground through the contacts of key 291.

Upon further rotation of impulsor switch 510, a circuit is established for operating relay 206. This circuit may be traced from grounded battery through the left winding of relay 206, left contact and armature of relay 227, brush 530 to ground through impulsor switch segment 541. Relay 206 in 25 operating, establishes a locking circuit for itself and an operating circuit for relay 228. The locking circuit may be traced from grounded battery through the right winding and right inner contacts of relay 206 to ground through the contacts of key 291. The operating circuit for relay 228 is obvious and need not be traced. The remaining circuits established by the operation of relays 206 and 228 connect ground and 35 grounded battery to the various lamp circuits.

The foregoing describes the register relay groups which are arranged on a coordinate basis. The relays forming the vertical ordinate grouping have not been placed on the drawing on a vertical line with each other. This is thought not to be material for an understanding of the relay grouping on a coordinate basis. The register relays of 40 Fig. 2 are arranged in two groups. Relays 607 to 610 inclusive form one group and relays 611 to 614 form another group. Selection is accomplished on a coordinate basis. Selection of a group may be termed 45 selection with respect to one ordinate and selection within the group may be termed selection with respect to another ordinate. This corresponds to the terminology which is used in connection with 100 point type 50 step-by-step switches in which the switch terminals are frequently spoken of as being arranged on a coordinate basis. In the case of the switch, the selection of a level or group is a selection with respect to one ordinate and selection within the chosen group is a selection with respect to a secondary ordinate.

Selection within the group in the present case is accomplished by means of brushes

526 to 529 inclusive and selection of a group 65 is determined by the action of any of the brushes other than the pick-up brushes when wired so as to control relays 231 and 229 which may be operated either independently or simultaneously. As a result, corresponding 70 relays in both groups may be simultaneously energized.

It will be remembered that relays 607, 608 and 609 of register A were operated and locked during one revolution of impulsor 75 switch 510. A circuit is now established to light lamp 6 of register A. This circuit may be traced from grounded battery through the right outer armature and contact of relay 206, conductor 240, left outer armature and contact of relay 608, lamp 6, left inner armature and contact of relay 607, left contact and armature of relay 609, right inner contact and armature of relay 608 to ground 80 through the contacts of key 291.

It will be remembered that relays 611 and 613 of register B were operated and locked during the same revolution of the impulsor switch that operated the relays of 85 register A. A circuit is now established to light lamp 7 of register B. This circuit may be traced from grounded battery through the left middle armature and contact of relay 228, conductor 256, left outer normal armature and contact of relay 612, left armature and contact of relay 613, left inner armature and contact of relay 611, lamp 7, right inner normal contact and armature of relay 612, to ground through the contacts of key 291.

Since lamp 6 of register A is lighted and lamp 7 of register B is lighted, number "67" is shown to indicate that a trunk or line of that number has been selected by switch 400.

After the number has been indicated by 105 the lighting of the lamp in registers A and B, an operator may actuate key 291 to release all of the relays that are held in a locked position. This includes relay 602, in addition to the register and control relays. Register 110 relays A and B may now be used for another registration upon the selection of a different trunk or line.

Impulsor switch 510 is used as a common 115 impulsor for a large number of switches, the same as switch 400. The contacts associated with brush 440 and 443 of switch 400 are connected to the brushes of the rotary impulsor switch in such manner as to operate certain of the register relays to indicate the 120 number of the trunk with which the brushes of switch 400 are associated. Several types of apparatus such as keys or primary registers may be used in the manner shown for switch 400 to control the pulses transmitted 125 through the rotary impulsor 510.

The following tabulations give in graphic form the various register relay combinations

obtainable with the registers A and B and with the rotary impulsing switch 510 for indicating the various digits of trunk designations. In this tabulation the numeral 5 441 is assumed for various conductors which may be connected to the switch terminals associated with brush 440 and the numeral 445 is assumed for various conductors connected to the switch terminals associated 10 with brush 443. Conductor 446 is one of the conductors like conductor 445 and is shown connected to brush 542 of the rotary impulsing switch. A switch of the type shown for switch 400 has a large number of 15 terminals associated with each brush and the conductors that connect the brushes of the rotary impulsing switch to the terminals associated with brushes 440 and 443 may be arranged in any desired combination to operate the relays of register A or B in any 20 of the desired combinations shown in the tabulation. An example may be assumed for lighting the zero lamp or register A and the No. 3 lamp of register B. From the tabulation, it is found that a conductor the same 25 as conductor 441 is connected from one of the switch terminals associated with brush 440 to rotary impulsor brush 529. When a conductor is so connected and brush 440 30 is resting on the terminal connected to this conductor, relay 608 is operated upon a rotation of the impulsor switch and lamp 0 is thus lighted. To light lamp 3 of register B, it is found from the tabulation that a conductor the same as conductor 445 is connected 35 to one of the switch terminals associated with brush 443 and is also connected to the rotary impulsor brush 526. With brush 443 resting upon a terminal so connected relay 40 611 is operated upon a rotation of the impulsor switch and lamp 3 is thus lighted.

Register A.

- Lamps.
- 45 0. Connect conductor 441 to brush 529—Relay 608 operated.
 1. Conductor 441 open (not connected)—All relays normal.
 2. Connect conductor 441 to brush 542—Relays 607 and 608 operated.
 3. Connect conductor 441 to brush 526—Relay 607 operated.
 4. Connect conductor 441 to brush 552—Relays 608 and 609 operated.
 5. Connect conductor 441 to brush 527—Relay 609 operated.
 6. Connect conductor 441 to brush 513—Relays 607, 608 and 609 operated.
 7. Connect conductor 441 to brush 514—Relays 607 and 609 operated.
 8. Connect conductor 441 to brush 553—Relays 608 and 610 operated.
 9. Connect conductor 441 to brush 528—Relay 610 operated.

Register B.

Lamps.

0. Connect conductor 445 to brush 529—Relay 612 operated.
 1. Conductor 445 open (not connected)—All relays normal.
 2. Connect conductor 445 to brush 542—Relays 611 and 612 operated.
 3. Connect conductor 445 to brush 526—Relay 611 operated.
 4. Connect conductor 445 to brush 552—Relays 612 and 613 operated.
 5. Connect conductor 445 to brush 527—Relay 613 operated.
 6. Connect conductor 445 to brush 513—Relays 611, 612, and 613 operated.
 7. Connect conductor 445 to brush 514—Relays 611 and 613 operated.
 8. Connect conductor 445 to brush 553—Relays 612 and 614 operated.
 9. Connect conductor 445 to brush 528—Relay 614 operated.

The invention claimed is:

1. In a controlling system, an impulse sending device, a registering device comprising a plurality of groups of relays arranged on a coordinate basis, energizing circuits for said relays, means to successively prepare said circuits with respect to their grouping as regards a primary ordinate and means to simultaneously and selectively complete said energizing circuits with respect to their grouping as regards a secondary ordinate under the control of said impulse sending device.

2. In a telephone exchange system, an impulse sending device, a registering device comprising a plurality of groups of relays, there being an equal number of relays in each of said groups, energizing circuits for said relays, means to simultaneously prepare said energizing circuits of a set of corresponding relays in all groups, and means to simultaneously and selectively complete circuits for desired ones of said corresponding relays under the control of said impulse sending device.

3. In a telephone exchange system, an impulse sending device, a registering device comprising a plurality of groups of relays, there being an equal number of relays in each of said groups, energizing circuits for said relays, means to simultaneously prepare said energizing circuits of a set of corresponding relays in all groups under the control of said impulse sending device, controlling relays, and means to operate said controlling relays in desired combinations under the control of said impulse sending device to simultaneously and selectively complete energizing circuits for desired ones of said corresponding relays.

4. In a telephone exchange system, an impulse sending device, a registering device

comprising a plurality of groups of relays, there being an equal number of relays in each of said groups, energizing circuits for said relays, means to simultaneously prepare 5 said energizing circuits of a set of corresponding relays in all groups, means to simultaneously and selectively complete circuits for desired ones of said corresponding

relays under the control of said impulse sending device, and locking circuits for said 10 relays complete upon energization from any of said relays.

In witness whereof, I hereunto subscribe my name this 19th day of September, A. D. 1923.

ALBEN E. LUNDELL.
